UNITED STATES PATENT OFFICE.

GEORGE H. ANDREW, OF BROOKLYN, WISCONSIN.

WINDMILL.

SPECIFICATION forming part of Letters Patent No. 254,527, dated March 7, 1882.

Application filed December 14, 1881. (Model.)

To all whom it may concern:

Be it known that I, GEORGE H. ANDREW, of Brooklyn, in the county of Green and State of Wisconsin, have invented certain new and useful Improvements in Windmills; and I do hereby declare that the following is a full, clear, and exact description of the invention, which will enable others skilled in the art to which it appertains to make and use the same, reference being had to the accompanying drawings, which form a part of this specification.

My invention relates to certain improvements in geared windmills, and has for its principal object to avoid the side drafts of wind which are common to ordinary geared windmills, and sometimes prove very disastrous thereto, by providing means for throwing the wheel out of gear. A further object is to so construct and arrange the gear-wheels that the wind-wheel will readily shift with the wind. These objects I attain by means of the devices illustrated in the annexed drawings, in which—

Figure 1 is a vertical central section; Fig. 2, a similar section taken on a plane at right angles to Fig. 1. Fig. 3 is a horizontal sectional view, and Fig. 4 is a central vertical section of a somewhat modified construction.

Referring by letter to the accompanying drawings, A indicates the frame which supports the several operative parts of the windmill.

B refers to the horizontal wind-wheel shaft, which has its bearings in standards b b, that are secured to the turn-table C of the windmill.

A bevel-gear, D, provided with an elongated hub or sleeve, d, is loosely mounted upon the wind-wheel shaft, and it is rigidly connected with a ring-gear, E, by means of the divergent arms F, that are in rigid connection with the sleeve of the said bevel-gear.

A crank-arm, G, is connected with the wind-wheel shaft at a point alongside of the ring-gear, and upon the wrist-pin of this crank-arm is a small loose gear, H, which meshes with the internal gear-teeth of said ring-gear, and which also gears with a spur-gear, i, that is rigidly secured to a large miter-gear, I. This miter-gear is loosely mounted upon the wind-wheel shaft, and is adapted to mesh with a horizontal miter-gear, K, that is mounted loose-

ly upon the vertical shaft L. An internally-toothed gear, M, is formed with or secured to the under side of the horizontal miter-gear K, and upon a horizontal arm, N, that is held stationary just above the turn-table, is arranged a small spur-gear, n, which engages with the internal teeth of the ring-gear M. This small spur-gear n also engages with a spur-gear, O, which is rigid upon the vertical shaft L. The horizontal arm upon which said spur-gear is mounted is provided at its outer end with a vertical pivot for the spur-gear, and at its inner end it is connected with a stationary tubular bearing, P, which is secured to the supporting-frame, and through which the vertical shaft passes. This tubular bearing passes through the turn-table, and also constitutes the axis about which the latter turns.

The vertical shaft L, which is employed for the purpose of actuating the pump or other mechanism to be driven, has a bearing at its upper end in a cross-bar, l, that is secured to standards upon the turn-table, and upon said shaft, below the cross-bar, is rigidly secured a bevel-gear, Q, which meshes with the large bevel-gear D, that is mounted upon the wind-wheel shaft, as already described.

When the wind-wheel shaft is revolved the bevel-gear D will revolve therewith by reason of the spur-gear H meshing with the gear i and the ring-gear E, which latter is, as before stated, in rigid connection with the bevel-gear D. This bevel-gear will then rotate the shaft L through the medium of the bevel-gear Q, that is secured to said shaft. During such movement on the part of the bevel-gears D and Q the horizontal miter-gear, engaging with the miter-gear I, will revolve in a direction reverse to the revolution of the vertical and the bevel-gear Q, which, as aforesaid, is secured upon said shaft. Thus as the vertical shaft rotates about its axis it carries with it the spur-gear O, which is rigid with said shaft. The horizontal miter-gear K, moving with the vertical miter-gear I, will revolve in a direction reverse to the movement of the spur-gear O by reason of the small spur-gear n, which has a free rotation about its axis on the stationary horizontal arm N. Hence as this spur-gear revolves it will, by reason of its engagement with the spur-gear O upon shaft L, turn in a direction reverse to the movement

of the shaft, while the miter-gear K, having the internal gear, M, with which the spur-gear n engages, will revolve in the same direction as said spur-gear.

5 In the modification shown in Fig. 4 the bevel-gear D is loosely mounted upon the wind-wheel shaft B. The ring-gear E, having internal gear-teeth, is in rigid connection with the said bevel-gear by means of a sleeve, d, and divergent arms F, as in Fig. 1.

The miter-gear I is attached to the wind-wheel shaft B, and meshes directly with a miter-gear, K, that is rigid upon the vertical shaft L. i is a spur-gear rigid upon the wind-wheel shaft B, and G indicates an arm loosely mounted upon said shaft and provided with pivots, upon which are loosely mounted the spur-wheels H. These spur-gears engage with and serve to connect the internally-toothed ring-gear E, 20 which is rigid with gear D, with the spur-gear i, that is rigid upon the wind-wheel shaft B.

Upon the vertical shaft L is a loose bevel-gear, Q, which is engaged by the bevel-gear D. This bevel-gear Q is provided upon its under 25 side with an internal gear, M, with which the spur-gear n upon the stationary arm N engages. This spur-gear also engages with a spur-gear, O, that is rigid upon the shaft L, and upon the upper end of this vertical shaft is the miter-gear K, arranged to engage with the miter-gear I upon the wind-wheel shaft. It will be seen that in both instances the same objects are attained, the wheels or gears D and I being opposite each other, and the remaining gears being practically the same in both cases.

The above arrangement admits of the wheel and turn-table readily shifting with the wind. Thus when the wind shifts the gear D will ride over the teeth of the gear Q, and the gear I 40 will ride over the teeth of the gear K.

Having thus described my invention, what I claim is—

1. The combination, in a windmill, of bevel-gear and the miter-gear upon the wind-wheel shaft, with the bevel-gear and the miter-gear 45 rotating about the axis of the vertical shaft and driven in opposite directions, one of said last two mentioned gears being rigid upon the vertical shaft, and the other being loosely arranged and connected by a spur-wheel with a 50 spur-gear upon the vertical shaft, substantially as described.

2. The combination, with the horizontal wind-wheel shaft, of the loose bevel-gear D, connected with an internally-toothed gear, E, and engaging with a bevel gear that is rigid upon the vertical shaft, the miter-gear I, engaging with the miter-gear K, the arm upon the horizontal shaft carrying a loose spur-gear engaging the internally-toothed wind-gear E and the spur-gear i, 60 the spur-gear n upon a stationary arm, N, and the gears O and Q upon the vertical shaft, said members being combined and organized for operation substantially as described.

3. The combination of the horizontal shaft 65 B with the bevel-gear D, the bevel-gear Q upon the vertical shaft, the miter-gears I and K, the spur-gears n O, and the internal gear, M, constructed and organized for operation substantially as specified.

In testimony that I claim the foregoing as my own I have hereto affixed my signature in presence of two witnesses.

GEORGE H. ANDREW.
